CLAIM

The ornamental design for an automobile console, as shown and described.

DESCRIPTION

FIG. 1 is a right side perspective view of an automobile console showing our new design;

FIG. 2 is a left side perspective view thereof;

FIG. 3 is a top view thereof; and,

FIG. 4 is a front view thereof.

It will be understood that the broken lines shown in the drawings illustrate portions of the automobile console that form no part of claimed design.

1 Claim, 4 Drawing Sheets

FIG. 3

FIG. 4
